UNITED STATES PATENT OFFICE.

MANUEL THOMASIAN, OF PHILADELPHIA, PENNSYLVANIA.

REPLACEABLE HEEL.

Application filed December 7, 1920. Serial No. 428,865.

To all whom it may concern:

Be it known that I, MANUEL THOMASIAN, a citizen of Turkey, having declared my intention of becoming a citizen of the United States, residing in Philadelphia, Pennsylvania, have invented certain Improvements in Replaceable Heels, of which the following is a specification.

My invention relates to improvements in heels for shoes, one object of my invention being to provide a heel both easily attachable and detachable which at the same time is retained firmly in place when attached under all normal conditions.

15 A further object is to provide means whereby the attaching means may be applied to the shoe without the use of nails.

In the attached drawings:

Figure 1, is a perspective view of a shoe 20 from which the detachable portion of the heel has been removed;

Fig. 2, is a perspective view of the detached heel portion;

Fig. 3, is a perspective view of the portion 25 of the retaining means which may be permanently secured within the heel proper of a shoe;

Fig. 4, is a perspective view of the portion 30 of the retaining means which is secured to the detachable portion of the heel;

Fig. 5, is a vertical section of a heel made in accordance with my invention, showing the detachable portion of the heel in place;

Fig. 6, is a view in perspective of a modified socket portion for use particularly in French heels;

Fig. 7, is a partial vertical section through a French heel made in accordance with my invention, and

40 Fig. 8, is a view in perspective of a rubber heel lift made in accordance with my invention.

With reference to the drawings, my device comprises a socket member 1 adapted to be secured in a suitable recess 2 in the under side of the heel 3 of a shoe in the manner clearly illustrated in Fig. 1. This socket member preferably comprises a substantially ring-like metal body portion 4 generally 45 of the usual heel shape, which body may have at one edge a laterally extending flange 4^a. This member is adapted to be attached to a heel lift 3^a in the manner most clearly shown in Fig. 5, the said lift 3^a being apertured to receive the body portion 4 of the socket member which, when inserted to the

full extent with the flange 4^a abutting one face of the lift, has a portion thereof extending beyond the opposite face, and this extending portion is then beaded over to 60 form a flange 4^b between which and the flange 4^a the said lift is confined, the lift and socket portion being thus united. The lift 3^a with the socket member attached may then be attached in the usual manner to the 65 shoe.

The male portion of the securing device consists of an element 5 which is preferably made of metal and which is adapted to fit within the said socket member 4. This male 70 element is in the present instance, as most clearly shown in Fig. 3, of generally cup-shape formation, the upper edges of the cup being serrated to form sharp pointed projections 5^a. The element 5 is attached to the bottom lift 3^b of the heel by driving the sharp pointed projections 5^a into the lift, after which the lift may be attached to the heel by inserting the said element in the 75 socket member.

When the male member 5 is inserted within the socket 1, the side wall 5^c of the male member frictionally engage the peripheral side walls 4^c of the socket member and holds the sections together, the top section of the male member 5 tending to stiffen the side walls 5^c of the male member to prevent their inward movement.

The side 4^c of the socket against which the side of the male element bears is preferably made slightly concave, the side 5^c of the male element being correspondingly convexed so that although it requires a considerable pressure to force the element into the socket, it remains firmly in place therein 85 and retains the top lift tightly against the heel. It is also preferred that a liner 6 of felt or other suitable material be interposed between the sides of the socket and male element, especially where the said sides are straight, said liner rendering the fit more perfect and tight. The said top lift is preferably beaded outwardly at the top edge thereof, forming a ledge 7, which extends slightly beyond the side faces of the heel, said ledge protecting the juncture of the heel and lift and preventing the entrance of water therebetween, while at the same time adding materially to the general appearance of the shoe. The upper surface of the said top lift may also be recessed to receive the lift 3^a, as shown in Fig. 5. It will be noted 100 105 110 115

that no nails are required in the formation of this heel.

In Fig. 6, I have illustrated a socket for use in French heels, this socket comprising a cup-shaped socket portion 8 having at the edges a flange 9, from the outer edge of which extend upwardly pointed projections 10. The socket is established within a recess formed for the purpose in the bottom of the heel 11, in the manner shown in Fig. 7, the projections 10 entering the material of the heel and holding the socket in place. It is preferable in this instance that nails 12 be employed to assist in retaining the socket member in the heel. The male member 13 which is attached to the top lift 14 may be similar in all respects to the member 5 previously described.

When employing the device in connection with a rubber heel lift, the male element may be attached in the manner shown in Fig. 8. In this instance, the element consists of a body portion 15 adapted to fit within its companion socket member as previously described, said body portion having a lateral flange 16 which is established in a suitable pocket formed in the rubber lift 17, the body portion projecting through an aperture in the upper face, as clearly shown.

The device provides means whereby the worn-out top lifts of the shoe may be replaced by new ones, or the lift of the left

shoe exchanged with the lift of the right shoe, so that the uneven wear which usually occurs in heels may be compensated. The provision of the closed top to the member 5 possesses decided advantages over a construction in which said top section is omitted, as the said top section materially stiffens the side walls and prevents their inward movement. The laterally extending flanges on the socket and male members also coact to stiffen and strengthen the heel and aid in providing a rigid and secure connection between these sections.

I claim:

In a replaceable heel, the combination with an apertured lift attached to a shoe, a socket member lining the side walls of said aperture and having a laterally extending bottom flange, and a hollow male member secured to the removable top lift of the heel and comprising a top section and downwardly extending side walls terminating in laterally extending bottom flanges, the side walls of the male member frictionally engaging the socket in the apertured lift and the top wall stiffening said side walls to prevent their inward movement, and the flanges of said socket and male members lying adjacent and coacting to stiffen and strengthen the heel when in its assembled position.

MANUEL THOMASIAN.
